UNITED STATES PATENT OFFICE.

HUGH LYONS, OF CHICAGO, ILLINOIS, ASSIGNOR OF ONE-HALF TO HENRY CORTRITE, OF LANSING, MICHIGAN.

AUTOMATIC DAMPER-REGULATOR.

SPECIFICATION forming part of Letters Patent No. 235,544, dated December 14, 1880.

Application filed October 23, 1880. (No model.)

To all whom it may concern:

Be it known that I, HUGH LYONS, of Chicago, in the county of Cook and State of Illinois, have invented certain new and useful Improvements in an Automatic Damper-Regulator for Steam-Boilers; and I do hereby declare the following to be a full, clear, and exact description of the invention, that will enable others skilled in the art to which it appertains to construct and make use of the same, reference being had to the accompanying drawings, and to the letters and figures of reference marked thereon, forming a part of this specification.

Figure 1 is a vertical longitudinal section of my improved damper-regulator; Fig. 2, a view of the same, taken in a plane at right angles relative to Fig. 1.

The object of this invention is an improvement in damper-regulators for steam-boilers, whereby a uniform pressure of steam may be maintained; and it consists of certain novel features in the construction and operation of the same, as will be hereinafter more fully described in detail, and set forth in the claims.

Referring to the drawings, A represents a cast-metal casing or butt. B is the cylinder; C, the piston; D, the piston-rod, and E the cap covering the upper end of the cylindrical body B.

The casing A is chambered for the reception of the piston-valve a, as shown in the drawings, the steam entering the valve-chamber at 3, and passing through the receiving steam-ports 4 in the under side of the valve a, into the annular recess or groove 5 cut in the periphery of the valve at a point a little above the lower end of the valve, as shown in the drawings. The steam passes to the cylinder B through the steam-passage 6, the steam exhausting from the cylinder through the passage 7 into the upper annular recess, 8, in the valve, and thence into the atmosphere through the exhaust-port 9.

The object of the annular recesses in the piston-valve is that it permits the steam to pass clear around the valve at these points, giving an equal pressure on all sides of the valve alike, imparting to the same something of the nature and action of a balance-valve,

obviating the liability of the valve sticking or becoming fast in the valve-chamber, and insuring a more positive and certain action of the same.

The greatest objection to this class of damper-regulators has been the liability of the valve to become stuck by having the pressure of the steam all on one side, which would often prevent the prompt action of the valve, and consequently the movement of the damper also.

The piston-valve is cylindrical in form, and has, substantially, a steam-tight bearing on the walls inclosing the valve-chamber. The upper end of the valve is provided with the conical cavity or recess 10 directly in the center of the same, this recess being for the reception of the lower end of the loose valve-stem 11, which is of a corresponding shape relative to the conical recess in the valve, as shown in the drawings. The upper end of the loose valve-stem is also cone-shaped, and fits into a recess in the lever 12.

The aperture in the casing A, through which the upper end of the loose valve-stem passes to engage with the under side of the lever 12, should be a little smaller than the largest part of the conical recess 10 in the valve, so that in play the valve-stem will have no contact or bearing on the valve other than on the extreme lower point of the same. Should the valve-stem bear against the sides of the conical-shaped recess it would have a tendency to bind the valve and prevent a free movement of the same. By this form of construction and arrangement of these parts the piston-valve is susceptible of a very sensitive action, and allowed but a slight variation of the steam-pressure either way before the damper is opened or closed.

The loose valve-stem is also provided with a shoulder, 13, which serves to prevent the valve-stem from dropping out of place each time that the lever 12 is removed and the device inverted. Much annoyance is experienced from the dropping out and loss of this loose valve-stem, from the fact that it is required to be of certain dimensions and of just such a length.

The piston-valve is prevented from moving

below a certain point by means of the pin or bolt 14.

The outer end of the lever 12 is broken away; but in practical use the same is provided with a graduating-scale and properly weighted.

As these features are neither new nor novel they are omitted from the description and drawings.

- 10 Attached to the piston-rod D is the toothed rack 15, which is adapted to engage with the pinion 16 placed on the shaft 17, which, in addition, carries the pulley 18 and the coiled spring 19, the shaft 17 resting in the bearings 20 placed upon the upper side of the cylinder-cap E. In practical use one end of the operating-cord is attached to and passes around the grooved pulley 18, the other end leading to and being attached to the lever operating the damper. The object of the coiled spring is to assist in forcing the piston on the downward stroke, thereby especially adapting the device to be used in connection with a low-pressure boiler, or to operate equally as well under a 25 low pressure of steam as under a high pressure, this being an objection to all of the damper-regulators now in use, from the fact that none of them would operate a damper under a pressure of less than twenty pounds.
- 30 One end of the coiled spring 19 is attached to the cap E and the opposite end inserted in the shaft 17, and so arranged that the upward movement of the piston will store up power in the spring to be exerted in forcing the piston downward.

The casing A, the cylinder B, and cap E are all distinct parts, and are clamped together by means of the rods or bolts 21.

- 35 The operation of this apparatus is as follows: The steam being admitted into the lower end of the valve-chamber, the valve is forced upward until the steam-passage leading to the cylinder is uncovered, when the steam passes

40 into the cylinder, forcing the piston upward, which movement causes the pinion to rotate 45 by means of its engagement with the toothed rack attached to the piston-rod. The upward movement of the piston closes the damper by means of the cord connecting the pulley 18 and the damper, the cord being wound around 50 the pulley as it rotates, and when the piston descends the cord is slackened and the weight on the damper causes the same to open.

Having thus described my invention, what I claim, and desire to secure by Letters Patent, 55 is--

1. In a damper-regulator, the piston-valve a, having the steam-receiving ports 4, and provided with the annular recesses or grooves 5 and 8, thereby adapting the valve to have an 60 equal pressure on all sides alike, substantially as and for the purpose described.

2. In a damper-regulator of the character hereinbefore described, the combination, with the casing A, provided with a chamber on the 65 interior thereof, of the piston-valve a, provided with the annular recesses or grooves 5 and 8 and the conical cavity 10, and the loose valve-stem 11, provided with the shoulder 13, substantially as and for the purpose herein described. 70

3. In a damper-regulator, the combination, with the cylinder B and the casing A, of the piston-valve a, provided with the annular grooves 5 and 8, all constructed and arranged 75 for operation substantially as herein shown, and for the purpose described.

4. In a damper-regulator, the combination, with the piston-rod D, of the toothed rack 15, the pinion 16, the shaft 17, the coiled spring 80 19, and the pulley 18, substantially as described.

HUGH LYONS.
